UNITED STATES PATENT OFFICE

FREDERICK E. HALL, OF NORTH EASTON, MASSACHUSETTS, ASSIGNOR TO THE CHASE COMPANIES, INCORPORATED, OF WATERBURY, CONNECTICUT, A CORPORATION

HAND-OPERATED AIR PUMP AND THE LIKE

Application filed April 8, 1931. Serial No. 528,619.

10 This invention relates to an improvement in pumps, and particularly to hand-operated reciprocating air-pumps such as tire-pumps, etc., though not so limited.

15 The main object of my present invention is to provide a reciprocating pump at a low cost for manufacture, with simple, reliable and effective lubricating-means.

20 Another object of my invention is to provide a pump with durable and effective means for checking the upstroke of the plunger with the minimum of shock and noise.

25 With the above and other objects in view as will appear from the following, my invention consists in a reciprocating pump having certain details of construction and combinations and arrangements of parts as will be hereinafter described and particularly recited in the claims.

30 In the accompanying drawing:

Fig. 1 is a view in side elevation of a reciprocating tire-pump embodying my invention;

35 Fig. 2 is a broken view, on a larger scale, in vertical longitudinal section, taken on the line 2—2 of Fig. 1, and showing the plunger in its depressed position;

40 Fig. 3 is a corresponding view, but showing the plunger at the limit of its upward stroke and the conical oil-reflector in engagement with the absorbent oil-storage pad;

Fig. 4 is a perspective view of the oil-storage pad detached;

45 Fig. 5 is a perspective view of the oil-reflector detached; and

Fig. 6 is a broken central longitudinal sectional view substantially corresponding to Fig. 3 but showing another form which my invention may assume.

For the illustration of my invention I have herein chosen a tire-pump comprising the usual features, consisting, as herein shown, of a foot-plate 10 secured in any approved manner to the lower end of a tubular sheet-metal cylinder 11, which latter is provided at its upper end with external threads 12 for inter-engagement with threads 13 formed upon the inner periphery of the skirt 14 of a sheet-metal cap 15.

55 The skirt-portion 14 of the cap 15 is, as shown, made smaller in diameter than the upper end of the cap to provide a retaining-shoulder 16 for the retention of an absorbent oil-storage pad 17 which will be hereinafter described in detail.

60 The cap 15 is also provided with an up-standing-boss 18 providing a chamber 19 and formed with an axial passage 20 for the guidance of a plunger-rod 21 which latter is provided at its upper end with the usual handle 22.

65 The plunger-rod 21, above referred to, passes through an axial passage 23 formed in the pad 17 and is provided at its lower end with the usual piston consisting of a cup-shaped flexible washer 24 clamped between a pair of complementary washers 25 and 26 which are, in turn, respectively engaged by clamping-nuts 27 and 28 applied to 70 the threaded lower end 29 of the said plunger-rod.

75 Mounted upon the upper surface of the washer 25 is a conical oil-deflector 30 preferably formed of sheet-metal so as to house the nut 27 and having its upper edge snapped into an annular groove or recess 31 formed in the plunger-rod 21 at a point slightly above the washer 25 and nut 27.

80 The fitting of the upper edge of the conical oil-deflector 30 into the groove 31 serves to prevent its axial displacement in an upward direction while the bearing of its lower edge upon the washer 25 serves to prevent its downward axial displacement.

85 The oil-storage pad 17 before referred to is provided in its under-face with a conical recess 32 substantially corresponding in form and size to the conical oil-deflector 30.

90 In the operation of the reciprocating pump above described, as the plunger approaches the limit of its upward stroke, the conical oil-deflector 30 will be brought into engagement with the surface of the conical recess 32 in the pad 17 so as to deflect the latter slightly upward into the chamber 19, with the result that a modicum of the oil stored in the said pad will be squeezed out and caused to flow down the surface of the said deflector 30 to a position adjacent the inner 95 100

surface of the cylinder 11 where it is most required to lubricate the same and maintain the cup-shaped washer 24 in a soft and pliable condition.

Furthermore, by virtue of the conical form of both the oil-deflector 30 and the recess 32 in the pad 17, the upward stroke of the plunger-rod 21 will be checked with the minimum of shock and noise.

10 It will be understood by those skilled in the art that my invention may assume varied physical forms without departing from my inventive concept and I, therefore, do not limit myself to the specific embodiment herein chosen for illustration, but only as indicated in the appended claims.

I claim:

1. In a reciprocating pump, the combination with the cylinder-unit and plunger-unit thereof; of an absorbent oil-storage pad carried by one of the said units; and a tapered oil-deflector carried by the other of the said units; the said pad and the said tapered oil-deflector being located within the pump structure in position to interengage as the said plunger-unit approaches the limit of its reciprocating movement to displace oil from the said pad toward the inner surface of the said cylinder-unit.

30 2. In a reciprocating pump, the combination with a cylinder-unit and plunger-unit thereof; of an absorbent oil-storage pad carried by one of the said units and formed with a tapered recess; and a tapered oil-deflector carried by the other of the said units; the said pad and the said tapered oil-deflector being located within the pump structure in position to cause the entry of the said deflector into the tapered recess in the said pad as the said plunger-unit approaches the limit of its reciprocating movement to displace oil from the said pad toward the inner surface of the said cylinder-unit.

45 3. In a reciprocating pump, the combination with a cylinder-unit and plunger-unit thereof; of an absorbent oil-storage pad carried by the said cylinder-unit; and a tapered oil-deflector carried by the said plunger-unit; the said pad and the said tapered oil-deflector being located within the pump structure in position to interengage as the said plunger-unit approaches the limit of its reciprocating movement to displace oil from the said pad toward the inner surface of the said cylinder-unit.

55 4. In a reciprocating pump, the combination with a cylinder-unit and plunger-unit thereof; of an absorbent oil-storage pad carried by the said cylinder-unit and formed with a tapered recess; and a tapered oil-deflector carried by the said plunger-unit; the said pad and the said tapered oil-deflector being located within the pump structure in position to cause the entry of the said deflector into the tapered recess in the said

pad as the said plunger-unit approaches the limit of its reciprocating movement to displace oil from the said pad toward the inner surface of the said cylinder-unit.

5. In a reciprocating pump, the combination with a cylinder, a cap therefor, and a plunger; of an absorbent oil-storage pad mounted in the said cap; a tapered oil-deflector carried by the said plunger; the said pad and the said tapered oil-deflector being located within the pump structure in position to interengage as the said plunger approaches the limit of its reciprocating movement to displace oil from the said pad toward the surface of the said cylinder.

6. In a reciprocating pump, the combination with a cylinder, a cap therefor, and a plunger; of an absorbent oil-storage pad mounted in the said cap and formed with a tapered recess; and a tapered oil-deflector carried by the said plunger; the said pad and the said tapered oil-deflector being located within the pump structure in position to cause the entry of the said deflector into the tapered recess in the said pad as the said plunger approaches the limit of its reciprocating movement to displace oil from the said pad toward the inner surface of the said cylinder.

7. In a reciprocating pump, the combination with the cylinder, a cap therefor, and a plunger; of an absorbent oil-storage pad mounted in the said cap with its central portion free for flexure in an axial direction; a tapered oil-deflector carried by the said plunger; the said pad and the said tapered oil-deflector being located within the pump structure in position to interengage as the said plunger approaches the limit of its reciprocating movement to displace oil from the said pad toward the surface of the said cylinder.

8. In a reciprocating pump, the combination with a cylinder, a cap therefor, and a plunger; of an absorbent oil-storage pad mounted in the said cap with its central portion free for flexure in an axial direction and formed with a tapered recess; and a tapered oil-deflector carried by the said plunger; the said pad and the said tapered oil-deflector being located within the pump structure in position to cause the entry of the said deflector into the tapered recess in the said pad as the said plunger approaches the limit of its reciprocating movement to displace oil from the said pad toward the inner surface of the said cylinder.

9. In a reciprocating pump, the combination with a cylinder and a plunger formed in its periphery with an anchoring-recess; of an absorbent oil-storage pad carried by the said cylinder; and a tapered sheet-metal oil-deflector mounted upon the said plunger and having its upper edge seated in the anchoring-recess therein; the said pad and the said tapered oil-deflector being located within the

pump structure in position to interengage as the said plunger approaches the limit of its reciprocating movement to displace oil from the said pad toward the inner surface of the said cylinder.

- 5 10. In a reciprocating pump, the combination with a cylinder, a cap therefor, and a plunger including a piston and a rod extending through the said cap; of an absorbent oil storage pad mounted in the said cap above the said piston and provided with a passage through which the rod of the said plunger extends; and means for retaining the said pad in said cap; the said pad being positioned to be engaged by a part of the said plunger as the same approaches the limit of its outward movement to displace oil for downward flow upon the said piston.
- 10 15

In testimony whereof, I have signed this specification.
